UNITED STATES PATENT OFFICE.

MYRON C. LISLE, OF MILWAUKEE, WISCONSIN, ASSIGNOR OF ONE-HALF TO JOHN KULZICK, OF MILWAUKEE, WISCONSIN.

BELT-CONNECTOR.

1,058,766.

Specification of Letters Patent.

Patented Apr. 15, 1913.

Application filed February 19, 1912. Serial No. 678,622.

To all whom it may concern:

Be it known that I, MYRON C. LISLE, a citizen of the United States, residing at Milwaukee, county of Milwaukee, and State of Wisconsin, have invented new and useful Improvements in Belt-Connectors, of which the following is a specification.

My invention relates to improvements in belt connectors.

10 The object of my invention is to provide a connector which will not open wholly or in part under the strains to which the belt is subjected.

It has heretofore been the practice to pro-

15 vide an ordinary wire link, the ends of which are hooked through the respective ends of the belt and folded inwardly. When the belt is subjected to strain, the inturned ends of the connector swing away from the

20 belt, forming projecting points which are apt to catch in the machinery or to tear the belt when the latter is crossed. I have dis-

25 covered that the tendency of the ends of the connector wire to spread is not due to a bending of the metal in the hooked portions of the connector, but to a flexion in the middle portion of the back, and I have there-

30 fore devised means whereby the back of the connector constitutes a truss, which will not bend under any ordinary strains, and I find that connectors made in this manner will re-

35 tain their shape throughout the hooked portions and at the inturned ends or points, the points remaining in clenching contact with

the surface of the belt on the inner side.

In the drawings—Figure 1 is a longitudinal sectional view of the meeting end portions of a belt with my improved connector applied thereto, the section being drawn to a plane to wholly expose the connector. Fig. 2 is a cross sectional view drawn through the central portion of the connector.

Like parts are identified by the same refer-

ence characters in both views.

45 My improved connector is preferably formed of wire and constitutes a link having a back A, hook shaped end portions B, adapted to pass through apertures in the belt, and inturned end portions C adapted to

50 clench or bear upon the inner surface of the belt adjacent to the meeting ends. The back A is widened in a plane at right angles to the surface of the belt to which it is applied, and is also narrowed in the transverse plane,

55 the material composing the connector being

flattened in a plane which includes the back A and the end portions C. The sides of the back A are preferably creased or indented in the middle portions, forming inner and outer ribs a' and a'' connected together by 60 a web a. The web a tapers to a point near the ends of the back A, the ribs a' and a'' converging and terminating in the hooked portions B, which are circular in cross section. The extremities of the inturned end portions C are preferably filed or ground off, as shown at D, to avoid cutting edges which might otherwise tear the belt when the latter is crossed.

It is desirable that the hooked portions B 70 should be circular in cross section, since they have less tendency to cut out the material composing the belt than if they were flattened or provided with squared angles.

The back portion A of the connector has no 75 tendency to cut the belt, however, and by flattening it in a plane perpendicular to the surface of the belt to which it is applied, an arch or truss is formed which possesses great

80 rigidity. The strength of this portion is still further increased by indenting the central portion of each side to form a web a, thus providing a greater amount of stock in the ribs a' and a'' for a given weight of ma-

terial. This is a consideration of great im-

85 portance to economy in manufacture, since the connectors can be most conveniently and cheaply formed from pieces of wire bent into the desired shapes and having the back pressed into the desired form from the origi-

90 nal cylindrical form of the wire.

I claim—

1. A belt connector formed integrally from a single piece of wire provided with in-

95 turned hook shaped end portions and a back

which is flattened transversely over the ex-

tremities of the hooks and enlarged at right

angles to the surface of the belt to form a

truss. 2. A belt connector provided with in-

100 turned hook shaped end portions circular in

cross section, and a back having a width in

105 a plane perpendicular to the surface of the

belt to which it is applied, greater than its

cross sectional dimensions of the hook por-

105 tions, the inner margin of the back being

formed to bear upon the ends of the belt,

when in a position of use.

3. A belt connector formed of wire and 110

provided with inturned hook shaped end portions, and having a flattened back in a plane which includes the inturned end portions, the outer and inner walls of said back 5 tapering from its central portion in the direction of the hook shaped end portions, and said hook shaped end portions having extremities beveled in the direction of the belt.

4. A belt connector comprising a back 10 composed of a pair of ribs connected by an integral central web and which converge toward the respective ends of the back, in combination with integral inturned hook shaped portions at the respective ends of the back.

5. A belt connector formed integrally 15 from a single piece of wire and having its back portion flattened in a plane perpendicular to the surface of the belt to which the back is applied, said connector having hooks at its respective ends, with inturned extremities in substantial alinement opposite the flattened back portion. 20

In testimony whereof I affix my signature in the presence of two witnesses.

MYRON C. LISLE.
